UNITED STATES PATENT OFFICE.

ALONZO N. SWINNEY, OF MACON, MISSOURI.

AUTOMATIC MOTOR STOP.

Application filed March 21, 1925. Serial No. 17,335.

This invention relates to what may be broadly referred to as an automatic motor stop, the same having particular reference to an automatically operable circuit closing device which serves to cut off the ignition when predetermined conditions are encountered.

The invention has more particular reference to a device of this class which is particularly adapted for use in connection with any internal combustion engine using a high pressure oiling system, it being the primary feature of the invention to eliminate possible damage caused by insufficient or inefficient lubrication, by automatically stopping the engine before the serious damage is done.

Insufficient lubrication may be due to the neglect of the operator to provide a sufficient amount of lubricating oil in the base or crank case, or it might be caused by accident or leakage which might escape the attention of the operator until the ignition circuit is broken by the improved automatic motor stop, thereby stopping the engine.

Inefficient lubrication is regarded an exceedingly detrimental danger to motor operations, due primarily to crank case dilution, such as cannot always be avoided, the presence of the improved automatic stop serving to break the ignition circuit and stop the motor when the oil does become diluted to a point where it is unfit for proper lubrication.

Briefly, the device comprises a casing in which a pressure gage siphon or spring is located for acting upon a counterbalanced circuit closer, the arrangement being such that so long as the oil pressure is sufficient, the circuit is closed, but that the moment that the pressure recedes below a danger point the circuit is broken.

The particular construction, features and other advantages of the invention will become apparent from the following description and drawing.

In the accompanying drawing forming a part of this application and in which like numerals are employed to designate like parts throughout the same:

Figure 1 is a side elevation of a device constructed in accordance with the present invention.

Figure 2 is a side or front view with the removable cover plate off, and portions broken away and shown in section to disclose the structure more clearly.

Figure 3 is a diagrammatic view showing the wiring system.

Referring to the drawing in detail, the reference character 1 designates a casing which, in practice may be of the approximate ovate shape shown or of any other appropriate configuration. This casing is provided at opposite points with apertured attaching ears 2, the front of the casing being open and adapted to be closed by a removable flanged cover 3. Fastened within the casing is a casting 4 which is preferably removably held in place by bolts or the like. This casting is provided with a bored passage 6 communicating at one end with an external screw threaded nipple 7 projecting beyond the rear face of the casing. It is to be stated here that the oil pressure pipe is adapted to be connected with this nipple. Connected in any appropriate way to this casting 4 is a crescent shaped tube composed of appropriate spring metal. A finger 9 is secured to the free end of the tube and is in turn pivotally connected to a link 10. This link is connected to the intermediate portion of an arm 11 pivoted as at 12 upon the aforesaid casting 4. The point of connection of the link is below the pivot. Carried on the upper end of the arm is a counterbalanced weight 13. On the lower end of the arm is a relatively movable contact element 14 adapted to cooperate with a relatively stationary contact element 15, the last named element being in association with the binding post 16, and the first named movable elements being electrically connected with a second binding post 17 through the medium of a wire 18. This wire 18 is of a length to permit free pivotal swinging movement of the arm 11. A conductor 19 is also connected with the binding post 16 and is adapted to lead to the coil (not shown) while a similar conductor 20 is connected to the binding post 17 and extends to a manually operable control switch located preferably upon the instrument board. In Figure 3 I have shown the approximate wiring diagram and by direct attention to this figure it will be seen that the last named conductor wire 20 is connected to one contact 21. Arranged in an arcuate line with the contact 21 is a second contact 22 from which a wire 23 leads to the battery. A still further contact 24 is provided from which a wire 25 leads to the coil.

A hand operated lever 26 is pivotally

mounted in any appropriate manner, and is provided with a fork 27, the arms of which are adapted to bridge the selected contacts 21, 22 and 24.

5 The case 1 may be of steel stampings, die casts or any appropriate metal shaped in any convenient fashion. The casing also constitutes or provides a base by means of which the device is securely fastened upon the instrument board, dash board, or any other place.

10 The casting 4 may be of brass, and of any convenient configuration, the same being screwed or otherwise detachably fastened 15 within the casing. The casting may be provided with an integral nipple 7 already described. The tube 8 may be of copper, one end being secured to the casting and the other end left free to move in a given line of 20 travel under the pressure produced therein by the oil pressure pump.

15 One of the most important details of the device is the counter-balanced arm 11 provided with the counterbalancing weight 13. 20 The counterbalance feature of this arm not only reduces friction at the pivot point, but eliminates vibration to a minimum, thereby making the device very sensitive to pressure and insuring positive action in actual practice as well as in theory. This counterbalanced arm is moved and controlled by means 25 of the aforementioned connecting link 10 which is in turn acted upon by the action of the pressure producing a movement of the copper tube. The parts are so arranged as 30 to produce an ideal ratio of movement of the link with respect to the contacts on the arm 11. Specifically, the ratio is approximately eight to one whereby to permit a comparatively 35 fast travel of the contact point with respect to the travel of the pressure operated tube, thus insuring a good solid and perfect contact of points through which the ignition circuit is properly maintained.

40 45 The binding posts or contact parts are all insulated from any adjacent metal part to protect the source of electrical supply and prevent the possible formation of ground which would impair the operation of the device. Although it is not essential, platinum 50 contact points are preferably used, this particular grade of metal having a very high fusing point that will withstand the electric arc occurring each time the electric circuit is 55 opened. The ignition hand operated switch used is of the three point type having one point connecting with the source of electrical supply or ignition circuit, while one of the other contact points is secured in a line direct 60 from the switch to the ignition coil or dis-

tributor set. This line is known as the starting line, indicated in the drawing. It is thought that the method of operation of the device including the proper positions of the switch is clear if the foregoing description 65 has been read carefully in connection with the accompanying drawing. Therefore, a more lengthy description is thought unnecessary.

70 The foregoing features are to be borne in mind. With the use of a manually controlled ignition switch, should the motor of an automobile, truck or other similar vehicle stop, due to low oil pressure, caused by dilution, the operator would still be able to throw the 75 switch over to starting position and drive the car for several miles until he could reach the filling station for a new supply of oil. The device will absolutely stop a motor in case that the automobile or other vehicle is 80 upset, thereby eliminating danger of fire and possibility of loss of life or limbs from this condition.

85 Although the preferred embodiment of the invention has been shown and described, it is to be understood that minor changes coming within the field of invention claimed may be resorted to if desired.

90 Having thus described the invention, what I claim as new is:—

95 As a new product of manufacture, a motor lubrication safety device of the class described comprising a casing of general ovate configuration, said casing comprising a hollow section open on one side having attaching ears, and a removable cover plate, a block-like casting mounted in said casing at one end, said casting being provided with a fluid passage with which a fluid pressure supply pipe is adapted to be connected, a 100 flexible fluid conducting tube connected at one end with the passage in said casting and having its free end located in said casing for movement in a predetermined arcuate path, an arm pivotally mounted between its ends on said casting, said arm having a counterbalance weight on one end, an electric contact carried by the opposite end of the arm, a fixed contact in said casing with which 105 said arm carried contact is cooperable, and a link connection between the free end of said tube and the intermediate portion of said arm, said tube being of flexible material and adapted to contain a fluid under pressure for flexing the same to assume a predetermined position and maintain the contacts in engagement with each other, under 110 normal lubricating conditions.

115 In testimony whereof I affix my signature.
ALONZO N. SWINNEY,
